UNITED STATES PATENT OFFICE.

JOHN TIEBOUT, OF BROOKLYN, NEW YORK.

DESIGN FOR A HINGE.

SPECIFICATION forming part of Design No. 17,044, dated February 1, 1887.

Application filed December 2, 1886. Serial No. 220,544. Term of patent 7 years.

To all whom it may concern:

Be it known that I, JOHN TIEBOUT, a citizen of the United States, residing at Brooklyn, in the county of Kings and State of New York, 5 have invented and produced a new and original Design for Hinges, of which the following is a specification, reference being had to the accompanying drawing.

This invention relates to a new and ornamental design for hinges, as hereinafter described, and illustrated in the accompanying drawing, which represents a plan view of one of my hinges.

In the drawing, the letters A B designate 15 the two leaves of my hinge, which are so placed in relation to each other that the leaf A extends at right angles to the leaf B. The outer edge of the leaf A forms two concave segments, *a b*, which meet in the middle, forming a point, *c*. The ends of the leaf A comprise a central leaf, *d*, and lateral leaves *e f*. The leaf B of the hinge is ornamented by con-

cave segments *g h*, which at their junctions form points *i i*. The segments *h h* meet the oblique lines *j j* at points *k k*, and the end lines, 25 *j j*, meet at a point, *l*.

What I claim as new, and desire to secure by Letters Patent, is—

1. The design for a hinge, consisting of the leaf A, having concave segments *a b* and leaves *d e f*, and the leaf B, having concave segments at its edge, as herein shown and described.

2. The design for a hinge, which consists of the concave segments *a b*, leaves *d e f*, concave segments *g h*, oblique end lines, *j j*, and points *i k l*, as shown and described.

In testimony whereof I have hereunto set my hand and seal in the presence of two subscribing witnesses.

JOHN TIEBOUT. [L. S.]
